UNITED STATES PATENT OFFICE

2,632,391.

CONSUMABLE CARTRIDGE

Warren H. Kintzinger, Cedar Rapids, Iowa

Application November 23, 1945, Serial No. 630,335

1 Claim. (Cl. 102—38)

1

This invention relates to improvements in guns and ammunition therefor.

An object of this invention is to provide a cartridge having a case containing the explosive charge made of a material which is consumed upon firing of the explosive charge. The use of such a cartridge eliminates the necessity for an ejector mechanism in the gun for the cartridge case, as is necessary for conventional cartridges. Because no ejector mechanism is necessary, the feeding of the cartridges to the gun and the firing of the cartridge may be greatly simplified.

Preferably, the cartridge case is of larger diameter than the projectile and the parts are secured together by a flange, the flange forming a shoulder on the cartridge. The primer is carried by the case adjacent the projectile and is detonated by a force acting on the flange or shoulder for firing the explosive charge.

Another object of this invention is to provide a gun for firing the cartridge of this invention in an improved and simplified manner. In this respect the gun has a bore for receiving and guiding the projectile and a cartridge chamber of larger diameter than the bore, there being a tapered shoulder between the bore and the cartridge chamber. A spring biased plunger advances the cartridge through the cartridge chamber toward the bore and when the shoulder of the cartridge strikes the tapered shoulder of the gun, the primer is detonated and the explosive charge fired, thereby propelling the projectile through the bore, retracting the plunger for the next firing cycle and consuming the cartridge case so that no ejector mechanism is necessary in the gun. When the plunger is retracted a new cartridge may be inserted in the cartridge chamber ready for the next firing cycle. Since no ejector mechanism is required and since new cartridges may be readily inserted in the cartridge chamber, more rapid firing of the gun is made possible.

A further object of this invention is to provide an improved means for controlling the advancing and retracting of the plunger which has particular utility in the type of gun of this invention. In this connection, the plunger is provided with a longitudinal groove and a sleeve surrounding the plunger is likewise provided with a longitudinal groove in alignment with the other groove. An arm is slidable from one groove to the other and a spring advances the arm. When the arm slides out of the groove in the sleeve into the groove in the plunger, the spring operates through the arm to advance the plunger and fire the cartridge. The explosive

2

force retracts the plunger, compresses the spring, and causes the arm to slide out of the groove in the plunger into the groove in the sleeve whereby the spring is cocked and the plunger is free. Another spring may be utilized for advancing the plunger when it is free of the first spring and this second spring may be weaker than the first spring. Trigger means may be utilized for holding the plunger retracted against the force of this weaker spring and may be readily released to permit advancing of the plunger. Because the trigger means acts in conjunction with the weaker spring, the trigger action may be made very sensitive, thereby greatly reducing the tendency of "pulling" the gun.

Other objects of this invention reside in the details of construction of the gun and the cartridge therefor, either alone or in combination.

Further objects and advantages of this invention will become apparent to those skilled in the art upon reference to the accompanying specification, claims, and drawing, in which—

Fig. 1 is a partial sectional view of one form of the gun of this invention;

Fig. 2 is an enlarged sectional view of a portion of the gun of Fig. 1 showing the gun in cocked position;

Fig. 3 is a sectional view similar to Fig. 2 but showing the gun in firing position;

Fig. 4 is a partial sectional view of another form of the gun of this invention;

Fig. 5 is an enlarged sectional view of a portion of the gun of Fig. 4 showing the gun in cocked position;

Fig. 6 is an enlarged sectional view similar to Fig. 5 but showing the gun in firing position;

Fig. 7 is a sectional view taken substantially along the line 7—7 of Figs. 2 and 5;

Fig. 8 is a sectional view taken substantially along the line 8—8 of Figs. 3 and 6;

Fig. 9 is a sectional view taken substantially along the line 9—9 of Figs. 2 and 5;

Fig. 10 is an enlarged sectional view of one form of the cartridge to be utilized in the guns of Figs. 1 and 4;

Fig. 11 is an elevational view looking from the right in Fig. 10;

Fig. 12 is a sectional view taken substantially along the line 12—12 of Fig. 10;

Fig. 13 is an enlarged sectional view of another form of the cartridge which may be utilized with the guns of Figs. 1 and 4;

Fig. 14 is an elevational view looking from the right in Fig. 13;

Fig. 15 is a sectional view taken substantially along the line 15—15 of Fig. 13.

Referring first to Figs. 10, 11 and 12, one form

of the cartridge of this invention is illustrated. The cartridge is generally designated at 10 and is provided with a projectile 11 having an annular groove 12. The projectile is adapted to be propelled by a charge of explosive 13 contained within a cylindrical case 14. The cylindrical case 14 is of larger diameter than the projectile 11 and is provided with a flange 15 for securing the projectile 11 and the case 14 together. Due to the differences in diameters between the projectile 11 and the case 14, the flange 15 forms an external shoulder on the cartridge. The flange 15 is provided internally with enlargements 16 for receiving a primer 17.

When a force is applied to the flange or shoulder 15 the primer 17 is detonated, thereby firing the charge of explosive 13 which acts to propel the projectile 11. The cartridge case 14 is made of a suitable material such as plastic made of explosive cellulose material which is burned or consumed upon firing of the explosive charge so that there is no need for ejecting the cartridge case from the gun as is required in conventional cartridges. The primer 17 being located adjacent the projectile 11 is readily ejected through the barrel of a gun along with the projectile. Also, by reason of this location of the primer, faster burning powder may be used in these cartridges as firing takes place immediately at the base of the projectile, no powder is moved, and, further, a clean explosion takes place.

The modified form of cartridge illustrated in Figs. 13, 14 and 15 includes the same projectile 11, explosive charge 13, case 14, and flange 15 cooperating with the groove 12. The essential difference between the cartridge of Fig. 13 with respect to that of Fig. 10 is the location of the primer. In Fig. 13 the cartridge case 14 is provided with internally located, oppositely disposed arms 18 and 19. The primer 20 is carried between the ends of the arms 18 and 19 so that when a force is applied to the flange or shoulder 15 of the cartridge case, that force is transmitted through the arms 18 and 19 for detonating the primer 20. While the details of construction are somewhat different in this form of the cartridge, the cartridge operates in substantially the same manner as that of Fig. 10 and obtains substantially the same results.

One form of a gun for firing the cartridges of Figs. 10 to 15 is illustrated in Figs. 1 to 3 and 7 to 9. The gun is generally designated at 25 and includes a barrel 26 carried by a suitable stock 27. The outer end of the barrel 26 is provided with a rifle bore 28 which is of such diameter to receive and guide the projectile 11 of the cartridge 10. The gun barrel also includes a cartridge chamber 29 for receiving the cartridges 10 and the cartridge chamber 29 is of larger diameter than the bore 28. The juncture between the bore 28 and the cartridge chamber 29 comprises a tapered shoulder 30 provided with flutes. A plunger 31, operated by a spring means to be explained more fully hereafter, advances the cartridge 10 from a position in the cartridge chamber 29 adjacent a cartridge magazine 32 through the cartridge chamber 29 toward the bore 28.

The spring means operates with considerable force in advancing the cartridge 10 and when the flange or shoulder of the cartridge 10 engages the fluted tapered shoulder 30 of the gun, the primer is detonated to fire the explosive charge in the cartridge. The projectile 11 is propelled through the bore 28 and due to the nature of the cartridge case it is consumed upon firing.

The explosive force which propels the projectile through the bore 28 also retracts the plunger 31 against the action of the spring means and when the plunger 31 is completely retracted, a new cartridge transfers from the magazine 32 to the cartridge chamber 29. The cartridge chamber 29 is of sufficient length to prevent the hot explosive gases from entering the magazine 32. The retracting action of the plunger 31 gives the same effect as though slower burning powder were utilized in the cartridge.

Because faster burning powder may be utilized in the cartridge 10 and because no ejector mechanism is required in the gun by reason of the self-consuming cartridge case, the gun is capable of more rapid firing than conventional guns utilizing slower burning powder and conventional ejecting mechanisms for the cartridge cases.

The spring means for advancing the plunger 31 and for controlling the retraction thereof is more clearly shown in Figs. 2, 3, 7 and 8. The plunger 31 is provided with a longitudinally extending groove 35 for receiving a pin 36 carried by the barrel of the gun. The groove 35 and pin 36 operate to prevent rotation of the plunger 31 as it is advanced and retracted.

A sleeve 37 mounted within the barrel 26 has a plurality of longitudinal grooves 38, four being utilized for purposes of illustration. The plunger 31 also includes a like number of longitudinal grooves 39, the grooves 39 being in alignment with the grooves 38. A plurality of arms 40 are adapted to operate in the grooves 38 and 39 and to slide from one set of grooves to the other set of grooves. As shown in Figs. 2 and 7, the arms 40 are located within the grooves 38, while in Figs. 3 and 8 they are located in the grooves 39.

The gun barrel 26 is provided with an enlarged bore 42 for slidably receiving an actuator 43. The actuator is provided with an internal opening permitting the plunger 31 to extend therethrough and is also provided with an annulus 44 for receiving the ends of the arms 40. The annulus 44 is of sufficient size to accommodate the arms 40 when they are in the outer position as shown in Fig. 2, or the inner position as shown in Fig. 3. One end of a compression spring 45 is located in a seat 46 in the actuator 43. The other end of the spring 45 is located in a seat 47 of a spring anchor 48. The spring anchor 48 is held stationary by a screw 49. The screw 49 when removed permits removal of the parts within the gun barrel and may also be utilized for adjusting the position of the spring anchor 48 and hence adjusting the compression of the spring 45. The spring 45 therefore operates to urge the actuator 43 to the right, which in turn operates through the arms 40 when they are located in the grooves 39 in the plunger 31 to advance the plunger 31.

The screw 49 carries a guide pin 51 which extends into a bore 52 in the plunger 31. The guide pin 51 is utilized for guiding a small spring 54. One end of the small spring 54 is seated in a spring seat 53 in the screw 49 and the other end of the spring 54 abuts against the end of the plunger 31. The small spring 54, therefore, at all times urges the plunger 31 toward the right. The force of the small spring 54 is considerably less than the force of the large spring 45. The spring anchor 48 is provided with a bore 55 for accommodating the small spring 54.

The plunger 31 is provided with a notch 57 adapted to receive a sear pin 58 of a trigger mechanism 59 for holding the plunger 31 in a retracted position.

With the parts in the position shown in Fig. 2, the plunger 31 is retracted and is being held in the retracted position by the sear pin 58 of the trigger mechanism. The sear pin 58 is holding the plunger 31 against the action of the small spring 54. The arms 40 are located in the grooves 38 of the sleeve 37 and are held in those positions by the plunger 31, it being noted that the grooves 39 in the plunger 31 are at the extreme left position. The large spring 45 is therefore cocked and is at this time exerting no force on the plunger 31.

When the trigger mechanism 59 is operated to release the sear pin 58 from the notch 57, the small spring 54 advances the plunger 31. As the plunger 31 advances the grooves 39 thereof in advance along the arms 40. When the right ends of the grooves 39 line up with the right ends of the arms 40, the spring 45 exerting a force on the arms 40 causes the arms 40 to enter the grooves 39 and when they enter the grooves 39 the large spring 45 then becomes effective to advance the plunger 31. The arms 40 are held within the grooves 39 by reason of the fact that they have now advanced beyond the grooves 38 in the sleeve 37. At this point, therefore, the force of the large spring 45 is added to that of the small spring 54 whereby the plunger 31 is therefore advanced rapidly with considerable force.

This rapid and forceful advancing of the plunger 31, carrying with it the cartridge 10, causes the shoulder or flange of the cartridge 10 to strike the tapered shoulder 30 of the gun with considerable force, thereby detonating the primer and firing the cartridge.

The explosive force causes retracting of the plunger 31 and in its initial retracting movement the plunger 31 operates against the heavy spring 45 and the light spring 54. The combined forces of these springs absorb much of the initial force of the firing, thereby controlling the retraction of the plunger 31.

As the plunger 31 retracts to a point where the right ends of the arms 40 line up with the grooves 38 in the sleeves 37, the arms 40 are slid into the grooves 38 by the plunger 31 and are held in the grooves 38 by the further retraction of the plunger 31. At this point, therefore, the force of the heavy spring 45 is removed from the plunger 31 whereby further retraction of the plunger 31 is against the light spring 54. At this time much of the explosive force has expended itself and because at this time retraction of the plunger 31 is being opposed only by the light spring 54, complete retraction of the plunger 31 is assured. When the plunger 31 is completely retracted in this manner, the sear pin 58 engages within the notch 57 to hold the plunger 31 retracted. In this manner a single firing of the gun may be accomplished. If the trigger mechanism 58 is maintained depressed so that the sear pin 28 is retracted, rapid firing of the gun may be obtained for just as soon as the plunger 31 becomes completely retracted it will start an advancing movement and the firing cycles will be continuous until such time as the sear pin 58 is released to engage in the notch 57.

The plunger 31 may be provided with a handle (not shown) extending outwardly from the gun, whereby the plunger 31 may be manually re-

tracted for the purpose of manual cocking of the gun. Also, the gun may be provided with the usual safety (not shown).

Figs. 4, 5 and 6, show a slightly modified form of the gun. Here the gun is generally designated at 65 and may include a barrel 66 suitably mounted in a stock 67. The bore 28, the cartridge chamber 29, the fluted tapered shoulder 30, the plunger 31, the cartridge magazine 32, the groove 35 and pin 36, the sleeve 37, the longitudinal grooves 38 in the sleeve, the longitudinal grooves 39 in the plunger, the arms 40, the actuator 43, the large spring 45, and the spring anchor 48 of this modified gun are the same as the corresponding parts of the gun of Figs. 1 to 3 and like reference characters have been utilized for like parts. These parts operate in the same manner in both guns and, therefore, a further description is not considered necessary.

Essentially, the main difference between the gun of Fig. 4 and the gun of Fig. 1 is that in Fig. 4 the trigger mechanism works in connection with the small spring rather than in connection with the plunger as in Fig. 1.

The gun of Figs. 4 to 6 includes a screw threaded plug 70 for locating the spring anchor 48. This screw threaded plug 70 is provided with a bore for slidably receiving a pin 71 which extends forwardly into a bore 72 within the plunger 31. The right end of the pin 71 normally engages the end of the bore 72 in the plunger 31. The screw threaded plug 70 has a spring seat 73 for receiving one end of a small spring 74. The other end of the small spring 74 engages a collar 75 carried by the pin 71 so that the spring 74 urges the pin 71 to the right and since the pin 71 engages the end of the bore 72 in the plunger 31, it also urges the plunger 31 in an advancing direction to the right.

The rear end of the pin 71 is provided with a shoulder portion 76 adapted to receive the sear pin 77 of a trigger mechanism 78. The rear end of the barrel 66 may be provided with a suitable plug 79 which may be removed for disassembly of the parts within the barrel 66.

With the parts in the position shown in Figs. 4 and 5, the plunger 31 is retracted, the pin 71 is also retracted, and the sear pin 77 is maintaining the pin 71 in the retracted position. The collar 75 on the pin 71 maintains the small spring 74 compressed. Because the plunger 31 is retracted, the arms 40 are within the grooves 38 in the sleeve 37 and the large spring 45 is compressed but is not exerting any advancing motion to the plunger 31.

When the trigger mechanism 78 is compressed the sear pin 77 releases the pin 71 whereupon the light spring 74 acts through the collar 75 on the pin 71 to advance the pin 71 and the plunger 31. When the plunger 31 has advanced a predetermined amount, the arms 40 then slide into the grooves 39 in the plunger 31, and the large spring 45 operates in conjunction with the small spring 74 to advance the plunger 31 rapidly and with considerable force to the firing position.

Upon firing of the cartridge 10, the plunger 31 is retracted against the action of the large spring 45 and the small spring 74 and when the plunger 31 has retracted a predetermined amount, the arms 40 slide into the grooves 38 in the sleeve 37, whereupon the large spring 45 becomes cocked and exerts no force on the plunger 31. Continued retracting movement of the plunger 31 beyond this point causes continued

retracting movement of the pin 71 and when the plunger 31 and the pin 71 are completely retracted, the sear pin 77 engages the shoulder portion 76 to hold the pin 71 in a retracted position ready for another firing cycle. By maintaining the sear pin 77 depressed, rapid firing of the gun may be accomplished.

The gun of Fig. 4 is therefore substantially the same as the gun of Fig. 1, both arrangements operating in substantially the same manner to 10 provide substantially the same results, the main distinction between the two being the manner in which the trigger mechanism controls the firing of the gun.

While for purposes of illustration various forms of this invention have been disclosed, other forms thereof may become apparent to those skilled in the art upon reference to this disclosure, and, therefore, this invention is to be limited only by the scope of the appended claim and prior art. 20

I claim as my invention:

A cartridge comprising, a projectile, a charge of explosive for propelling the projectile, a cylindrical case containing the charge of explosive and having a flange for attachment to the projectile, a pair of oppositely disposed arms ex-

5 tending inwardly from the flange, said cylindrical case adapted to be consumed upon firing of the explosive charge, and a primer carried between the oppositely disposed arms to be detonated by a force acting at the flange through the arms for firing the explosive charge.

WARREN H. KINTZINGER.
